UNITED STATES PATENT OFFICE.

JAMES H. SAGER, OF ROCHESTER, NEW YORK.

DESIGN FOR A BLOCK FOR BICYCLE-CLIPS.

SPECIFICATION forming part of Design No. 29,628, dated November 8, 1898.

Application filed December 30, 1897. Serial No. 664,741. Term of patent 7 years.

To all whom it may concern:

Be it known that I, JAMES H. SAGER, a citizen of the United States, and a resident of Rochester, in the county of Monroe and State of New York, have invented and produced a new and original Design for a Block for Bicycle-Clips, of which the following is a specification.

My invention consists in the form and contour of the block for bicycle-clips shown in the accompanying drawings, in which—

Figure 1 is a perspective view of a block embodying my design as seen from the outer side, and Fig. 2 is a perspective view of the same or a like block as seen from the inner side.

The leading or characteristic feature of my device consists of the configuration shown in the accompanying drawings and herein described.

As shown in the drawings, the said block has two exterior convex cylindrical curvatures A A', joined by a slight indentation A².

The sides B and B' of said block are parallel, or substantially so, and a perforation C passes 25 transversely through said block a little above its middle point. The inner face of the block has at the upper portion an angular notch D, forming with the outer curvature A an edge d at the extreme upper end. Next to said 30 notch is a flattened portion D', through which the perforation C emerges. Next beneath said flattened portion D' is a portion having a general concave contour and provided on its face with a series of steps d², which steps 35 are substantially at right angles to the side faces B B' of the block. The stepped portion is continued in a convex lower end portion D³, which merges into the convex portion A'.

What I claim is—

The design for a block for bicycle-clips, substantially as shown and described.

JAMES H. SAGER.
